(57) **CLAIM**

The ornamental design for a battery housing, as shown and described.

DESCRIPTION

The patent or application file contains at least one drawing executed in color. Copies of this patent or patent application

publication with color drawing(s) will be provided by the Office upon request and payment of the necessary fee.

FIG. 1 is a top perspective view of a battery housing, showing a first embodiment;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a bottom view thereof;

FIG. 8 is a top perspective view of a battery, showing a second embodiment;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top view thereof;

FIG. 14 is a bottom thereof;

FIG. 15 is a top perspective view a battery housing showing a third embodiment;

FIG. 16 is a front elevation view thereof;

FIG. 17 is a rear elevation view thereof;

FIG. 18 is a left side elevation view thereof;

FIG. 19 is a right side elevation view thereof;

FIG. 20 is a top view thereof;

FIG. 21 is a bottom view thereof;

FIG. 22 is a top perspective view of a battery housing showing a fourth embodiment;

FIG. 23 is a front elevation view thereof;

FIG. 24 is a rear elevation view thereof;

FIG. 25 is a left side elevation view thereof;

FIG. 26 is a right side elevation view thereof;

FIG. 27 is a top view thereof;

FIG. 28 is a bottom view thereof;

FIG. 29 is a top perspective view of a battery housing showing a fifth embodiment;

FIG. 30 is a front elevation view thereof;

FIG. 31 is a rear elevation view thereof;

FIG. 32 is a left side elevation view thereof;

FIG. 33 is a right side elevation view thereof;

FIG. 34 is a top view thereof;

FIG. 35 is a bottom view thereof;

FIG. 36 is a top perspective view of a battery housing showing a sixth embodiment;

(Continued)

FIG. 37 is a front elevation view thereof;
FIG. 38 is a rear elevation view thereof;
FIG. 39 is a left side elevation view thereof;
FIG. 40 is a right side elevation view thereof;
FIG. 41 is a top view thereof; and,
FIG. 42 is a bottom view thereof.
The broken lines shown in the drawings depict portions of the battery housing which form no part of the claimed design.
